UNITED STATES PATENT OFFICE

JAMES S. REID, OF CLEVELAND, OHIO, ASSIGNOR TO THE EATON AXLE AND SPRING COMPANY, OF CLEVELAND, OHIO, A CORPORATION OF OHIO

CLOSURE

Application filed January 14, 1929. Serial No. 332,277.

This invention relates to improvements in bayonet-joint closures of the type provided with opposed locking fingers for cooperative engagement with opposed cam portions of the device having the opening to be closed. Such closures are used, for example, with the radiators and the fuel tanks of automobiles, and in order to prevent the escape of the contents of said receptacles, sealing gaskets of cork or like material are interposed between the closures and the parts of the receptacles to which they are connected. These gaskets in many instances are maintained in assembly with the closures by the locking members thereof, and in order to remove such gaskets when they are worn out (and gaskets of cork deteriorate more or less rapidly), the locking members must be removed and this is usually a difficult task.

It is therefore the object of the present invention to provide an improved closure of this type, having assembled therewith a sealing gasket of cork or like material, with said gasket maintained in assembly with the closure by the locking member thereof, simple yet effective means being provided for permitting the ready removal of the locking member to enable the old gasket to be easily and quickly replaced by a new one; and which closure is of extremely simple and inexpensive construction so that it can be made and sold at low cost.

Further objects of the invention are in part obvious and in part will appear more in detail hereinafter.

In the accompanying drawing, Fig. 1 is a vertical sectional view of the present improved closure detachably connected to a tubular neck, the view through the closure being on the line 1—1, Fig. 2; Fig. 2 is a cross sectional view of said closure on the line 2—2, Fig. 3; Fig. 3 is a side elevation of said closure, with parts broken away to show interior construction; Fig. 4 is a top plan view of the tubular neck shown in Fig. 1; and Fig. 5 is a central vertical sectional view of said neck on the line 5—5, Fig. 4.

In the present embodiment of the invention, the device to which the closure is adapted to be connected is a tubular neck which may

be an integral part of a receptacle, such as an automobile radiator or an automobile gasoline tank, or separate therefrom and suitably secured thereto around an opening thereof.

The neck here illustrated is a separate one piece member and includes a cylindrical body portion 1 provided at its base with an outwardly extending annular flange 2 for welding or other suitable securement to the receptacle 3 around the opening 4 thereof. Said body portion is provided at its upper end, which is the end to be closed, with an inwardly extending annular wall 5 which terminates in a depending flange 6. At two diametrically opposite points, parts of the wall 5 and the flange 6 are cut away, which divides the flange 6 into two portions and provides two passageways 7 which afford access for the closure locking fingers (to be later described) to the cam surfaces 8 on the bottom edges of the two flange portions 6 thus formed. Each such cam surface is provided at its "high" end with a dwell 9 to receive a closure finger when the closure is completely or fully connected to the neck, and just beyond these dwells, each flange portion 6 is provided with a depending stop projection 10 to limit rotary movement of the closure locking fingers up along the cam surfaces 8, all as will be readily understood.

The present improved closure includes a metal body member having a circular top portion 15 and a depending cylindrical skirt portion 16 slightly larger in diameter than that of the neck body portion 1 with which it is adapted for telescopic cooperation, as indicated in Fig. 1. Centrally arranged within said body member is an inverted cup-shaped supporting member with which is associated the locking member of the closure. Said cup-shaped member includes a cylindrical side portion 17 and a circular top portion 18 secured against the lower surface of the body member top portion 15 by any suitable means, such as by the tongues 19 which are struck up from portion 18 and imbedded in the metal of said body member top portion. Arranged within said inverted cup-shaped supporting member at the upper end thereof is a metal ring 22 having its upper edge in engagement

with the top portion 18 of said member and its cylindrical side wall in engagement with the cylindrical side portion 17 thereof. Secured against the lower edge of this ring is the locking member of the closure, which is here shown as a substantially flat, generally circular sheet metal disc 24 provided with two circumferential slots 25 extending inwardly from the outer edge of the disc in opposite directions and terminating beyond the disc center in apertures 26, said apertures being necessary or at least desirable for manufacturing purposes. Said slots provide two circumferentially extending, opposed locking fingers 27 of resilient character, the outer or free ends 28 of which are arched upwardly in cross section and project outwardly through opposed openings 30 in the cylindrical side portion 17 of the inverted cup-shaped supporting member, said openings being of appreciable height and being here shown as extending to the lower edge of said side portion.

The means here shown for securing the locking member against said ring is a sheet metal cross bar 35 having reduced ends 36 sprung into opposed apertures 37 in the side portion 17 of the cup-shaped securing member. Said bar lies between the two locking fingers of the locking member in abutting relation with the lower surface thereof, as best shown in Fig. 2.

The closure is connected to the neck in the usual manner of bayonet-joint connections, the projecting ends 28 of the closure locking fingers being passed down through the neck passageways 7. The closure is then turned in a clockwise direction which causes said finger ends to yieldingly ride up the neck cam surfaces 8 until they reach the dwells 9 thereof, further rotary movement of said fingers in this direction being prevented by the stop projections 10. As said finger ends travel up said cam surfaces, the free end portions of the closure fingers freely move downwardly with respect to the central or body portion of the locking member, as clearly indicated in Fig. 1, the resiliency of said fingers permit the closure to be very easily connected to and disconnected from the neck.

To remove the closure from the neck, it is only necessary to turn the closure in a counter-clockwise direction, which causes the finger ends 28 to leave the dwells 9 and ride down the cam surfaces 8 to the passageways 7, whereupon the closure can be readily separated or removed from the neck.

In order to prevent the escape of the contents of the receptacle 3 to which the neck is secured, the present closure is provided with a cork sealing gasket 40, as is usual. Said gasket is of annular form and so closely or snugly surrounds the upper end of the cylindrical side portion 17 of the closure supporting member that it is normally held in this position. When the closure is applied to the

neck, as in Fig. 1, said gasket is compressed between the closure top portion 15 and the neck wall 5, and when the closure is removed from the neck, the gasket remains in assembly with the closure, for it cannot escape therefrom due to the fact that the closure locking finger ends 26 project outwardly beyond the inner edge of the gasket, as best indicated in Fig. 2.

It will thus be seen that the locking member must be removed in order to enable the sealing gasket to be removed when necessary, and the life of these cork gaskets is comparatively short, because they harden and deteriorate rather quickly. With the present improved construction, the locking member can be easily removed, such removal being effected by simply inserting a screw driver or the like beneath the middle portion of the sheet metal cross bar 35 and pulling the ends 36 of said bar out of the slots 37 in the closure securing member. The removal of this cross bar permits the locking member to drop out of the closure securing member and the sealing gasket readily slid therefrom. When a new gasket has been put in position around the closure securing member and the locking member once again inserted therein with said locking member ends 28 projecting through the openings 30 thereof, the ends 36 of the cross bar are once again sprung into the slots 37 of said securing member, which maintains the gasket and the locking member in proper assembled relation with the closure securing member, all as will be readily understood.

As indicated in Fig. 2, the locking fingers 27 lie on opposite sides of said cross bar 35 so that said bar does not interfere with the movement of said finger ends 28 in openings 30 of the closure supporting member.

What I claim is:

1. A bayonet-joint closure for the ends of tubular necks having opposed cam portions adjacent the ends to be closed, comprising a locking member provided with outwardly extending locking fingers for cooperative engagement with the cam portions of such a neck, a supporting member for said locking member, a sealing gasket maintained in assembly with the closure by the locking fingers of said locking member, and resilient means releasably secured to said supporting member for maintaining the locking member in assembly with said supporting member, the resiliency of said means permitting its ready release from said supporting member to enable the locking member to be disassembled from said supporting member and the sealing gasket freed from its assembly with the closure.

2. A bayonet-joint closure for the ends of tubular necks having opposed cam portions adjacent the ends to be closed, comprising a locking member provided with outwardly

- extending locking fingers for cooperative engagement with the cam portions of such a neck, a supporting member for said locking member provided with two opposed apertures, a sealing gasket maintained in assembly with the closure by the locking fingers of said locking member, and resilient means releasably secured in the apertures of said supporting member for maintaining the locking member in assembly with said supporting member, the resiliency of said means permitting its ready release from said supporting member to enable the locking member to be disassembled from said supporting member and the sealing gasket freed from its assembly with the closure. 5
3. A bayonet-joint closure for the ends of tubular necks having opposed cam portions adjacent the ends to be closed, comprising a locking member provided with outwardly extending locking fingers for cooperative engagement with the cam portions of such a neck, a supporting member for said locking member, a sealing gasket surrounding said supporting member and maintained in assembly with the closure by the locking fingers of said locking member, and resilient means releasably secured to said supporting member for maintaining the locking member in assembly with said supporting member, the resiliency of said means permitting its ready release from said supporting member to enable the locking member to be disassembled from said supporting member and the sealing gasket freed from its assembly with the closure. 10
4. A bayonet-joint closure for the ends of tubular necks having opposed cam portions adjacent the ends to be closed, comprising a locking member provided with outwardly extending locking fingers for cooperative engagement with the cam portions of such a neck, a member within which said locking member is supported and provided with openings through which extend the locking fingers of said locking member and also provided with a pair of opposed apertures, a sealing gasket maintained in assembly with the closure by the locking fingers of said locking member, and a single resilient element releasably secured in the apertures of said supporting member for maintaining the locking member in assembly with said supporting member, the resiliency of said element permitting its ready release from said supporting member to enable the locking member to be disassembled from said supporting member and the sealing gasket freed from its assembly with the closure. 15
5. A bayonet-joint closure for the ends of tubular necks having opposed cam portions adjacent the ends to be closed, comprising a locking member provided with outwardly extending locking fingers for cooperative engagement with the cam portions of such a neck, a supporting member for said locking member in assembly with said supporting member, the resiliency of said means permitting its ready release from said supporting member to enable the locking member to be disassembled from said supporting member and the sealing gasket freed from its assembly with the closure. 20
6. A bayonet-joint closure for the ends of tubular necks having opposed cam portions adjacent the ends to be closed, comprising a locking member having a body portion and opposed locking fingers extending outwardly therefrom for cooperative engagement with the cam portions of such a neck, a tubular member within which the body portion of said locking member is arranged and provided with opposed openings outwardly through which extend the locking fingers of said locking member, a sealing gasket surrounding said tubular member and being prevented from escaping therefrom by the outwardly extending locking fingers of said locking member, and a resilient element arranged within and releasably secured to said supporting member for maintaining the locking member in assembly with said supporting member, the resiliency of said element permitting its ready release from said supporting member to enable the locking member to be disassembled from said supporting member and the sealing gasket freed from its assembly with the closure. 25
7. A bayonet-joint closure for the ends of tubular necks having opposed cam portions adjacent the ends to be closed, comprising a locking member having a body portion and opposed locking fingers extending outwardly therefrom for cooperative engagement with the cam portions of such a neck, a tubular member within which the body portion of said locking member is arranged and provided with opposed openings outwardly through which extend the locking fingers of said locking member, said fingers having vertical movement in said openings, a sealing gasket surrounding said tubular member being prevented from escaping therefrom between outwardly extending locking fingers of said locking member, and a resilient element arranged within and releasably secured to said supporting member for maintaining the locking member in assembly with said supporting member, said locking fingers lying on opposite sides of said resilient element so that the movement of said fingers in said tubular member openings is not interfered with by said resilient element, the re- 30

siliency of said element permitting its ready release from said supporting member to enable the locking member to be disassembled from said supporting member and the sealing gasket freed from its assembly with the closure.

8. A bayonet-joint closure for the ends of tubular necks having opposed cam portions adjacent the ends to be closed, comprising a locking member having a body portion and opposed locking fingers extending outwardly therefrom for cooperative engagement with the cam portions of such a neck, a tubular member within which the body portion of said locking member is arranged and provided with opposed openings outwardly through which extend the locking fingers of said locking member, and also provided with a pair of opposed apertures, a sealing gasket surrounding said tubular member being prevented from escaping therefrom by the outwardly extending locking fingers of said locking member, and a resilient element arranged within said supporting member releasably secured in the apertures thereof for maintaining the locking member in assembly with said supporting member, the resiliency of said element permitting its ready release from said supporting member to enable the locking member to be disassembled from said supporting member and the sealing gasket freed from its assembly with the closure.

9. A bayonet-joint closure for the ends of tubular necks having opposed cam portions adjacent the ends to be closed, comprising a locking member provided with outwardly extending locking fingers for cooperative engagement with the cam portions of such a neck, a supporting member for said locking member provided with two opposed apertures, a sealing gasket maintained in assembly with the closure by the locking fingers of said locking member, and a resilient sheet metal member having its two end portions releasably secured in the apertures of said supporting member for maintaining the locking member in assembly with said supporting member, the resiliency of said sheet metal member permitting its ready release from said supporting member to enable the locking member to be disassembled from said supporting member and the sealing gasket freed from its assembly with the closure.

10. A bayonet-joint closure for the ends of tubular necks having opposed cam portions adjacent the ends to be closed, comprising a locking member provided with outwardly extending locking fingers for cooperative engagement with the cam portions of such a neck, a supporting member for said locking member provided with two opposed apertures, a sealing gasket maintained in assembly with the closure by the locking fingers of said locking member, and a resilient sheet

metal member having its end portions reduced to fit the apertures of said supporting member in which said end portions are releasably secured for maintaining the locking member in assembly with said supporting member, the resiliency of said sheet metal member permitting its ready release from said supporting member to enable the locking member to be disassembled from said supporting member and the sealing gasket freed from its assembly with the closure.

In testimony whereof I hereby affix my signature.
